UNITED STATES PATENT OFFICE

JOSEPH M. KENNEDY, OF ST. LOUIS, MISSOURI

BOTTLE

Application filed November 21, 1929. Serial No. 408,729.

This invention relates generally to bottles and more specifically to an improved bottle provided with means for measuring a predetermined amount of liquid therefrom, the 5 predominant object of the invention being to provide a bottle of this type which is so constructed that it will not be necessary for the user of the bottle to be provided with a spoon or other measuring device for the 10 purpose of removing predetermined amounts of the liquid contents from the bottle.

As is quite generally known medicine and other liquids which are dispensed in bottles usually are used by withdrawing predetermined amounts of the liquids from the bottles, 15 in the case of medicines these amounts ordinarily being in doses of one or more tea-spoonfuls of the medicine. It frequently happens that the user of such a bottle is not provided with a teaspoon, as in home the tea-spoons may be in a remote part of the house, while in the case of person who is required 20 to carry a bottle of medicine about on his person a spoon is seldom at hand because of the inconvenience of carrying and using 25 same.

To obviate the necessity that a person be provided with a spoon for measuring out amounts of the liquid in a bottle, I have devised the bottle disclosed herein which briefly 30 stated is provided with a neck portion having a measuring well or compartment therein. In the use of the bottle same is tipped upwardly so as to cause the measuring well or compartment to be filled with liquid from the contents of the body portion of the bottle after which the bottle is returned to its 35 upright position to cause the main body of the liquid in the bottle to be returned to the body portion of the bottle whereby the liquid in the measuring well or compartment is 40 trapped and segregated from the remaining liquid in the bottle. The user may then pour out the contents of the measuring well or compartment into a receptacle or may raise 45 the bottle to the lips and discharge the contents of the measuring well or compartment into the mouth, whereby a predetermined amount of the liquid will be taken.

50 Figure 1 is a vertical section of the upper

portion of a bottle constructed in accordance with this invention.

Figure 2 is a view similar to Figure 1 but showing the bottle when it is tipped up to fill the measuring well or compartment. 55

Figure 3 is a view similar to Figures 1 and 2 but showing the bottle after it has been returned to its upright position after the tipping operation and after the position of the cork of the bottle has been altered. 60

Figure 4 is a view similar to Figures 1, 2, and 3, illustrating the manner in which the measured liquid is withdrawn from the measuring well or compartment. 65

Figure 5 is a plan view of the bottle as illustrated in Figure 1. 65

Figure 6 is a horizontal section on line 6—6 of Figure 1.

In the drawing, wherein is shown for the purpose of illustration, merely, one embodiment of the invention A designates my improved bottle which comprises a body portion B and a neck portion C. The body portion B of the bottle A is constructed in the manner common to bottles of the type to which this 70 invention relates and therefore, in the drawing, the lower portion of said body portion has been broken away to conserve space. 75

The neck portion C of my improved bottle is so formed that a measuring well or compartment 1 is provided within said neck portion, said measuring well or compartment being defined by the opposite side walls 2 of the neck portion C (Figure 6), a front wall 3, a rear wall 4, and a bottom wall 5. The front wall 3 and the rear wall 4 of the measuring well or compartment 1 terminate some distance below the top of the neck portion C and extended outwardly and upwardly from said front wall 3 is a pouring lip 6. 80 85 90

The neck portion C of the bottle A includes a curved rear wall 7 which is spaced apart from the rear wall 4 of the measuring well or compartment 1 to provide a passageway 8, said passageway communicating with the 95 body portion of the bottle and with the space above the measuring well or compartment 1. Also the neck portion C of the bottle is provided with a top portion 9 having an aperture 10 formed therein, and 11 designates a cork 100

which is arranged in said aperture 10. The cork 11 is provided with a cutaway portion which provides an inclined face 12 and the top face of said cork is cut away as indicated at 13, said cutaway portion 13 being on the same side of the cork as the inclined face 12.

When my improved bottle is not in use it is disposed in an upright position as illustrated in Figure 1, and the cork 11 of the bottle is positioned as shown in the view referred to; that is to say the face 11' of the cork will close the opening 6' leading to the lip 6. Because of this arrangement it is plain that the liquid within the bottle may not escape therefrom when the bottle is handled or if it should accidentally be overturned. When the cork 11 is arranged as described it will be noted that the interior of the body portion of the bottle is in direct communication with the measuring well or compartment 1 through the instrumentality of the passageway 8 and the space between the inclined face 12 of the cork and the top edge of the rear wall 4 of said measuring well or compartment.

Assume now that it is desired to withdraw from the bottle a predetermined amount of the liquid contained therein. The measuring well or compartment 1 is of such dimensions that it will hold a predetermined amount of liquid, a teaspoonful for instance, and by tipping the bottom of the bottle upwardly, as illustrated in Figure 2, liquid within the bottle will be caused to fill the measuring well or compartment 1 and the space within the neck portion of the bottle adjacent to said measuring well or compartment. During such tipping of the bottle it is obvious that the cork 11 will prevent passage of liquid from the bottle through either the opening 6' or the opening 10. When the liquid within the bottle has passed into the neck portion of the bottle as described and has filled the measuring well or compartment 1 the bottle is returned to its upright position when the liquid within the measuring well or compartment 1 will be trapped therein as illustrated in Figure 3. The cork 11 is then withdrawn from the opening 10 at the top of the neck portion of the bottle and said cork is reversed and replaced in said opening 10, and such reversal of the cork will cause the inclined face 12 to be located at the lip side of the bottle neck instead of the side opposite to the lip as in Figures 1 and 2. With the cork arranged as illustrated in Figure 3 the measuring well or compartment 1 is placed in communication with the opening 6' leading to the lip 6 and, therefore, the contents of the measuring well or compartment may be poured therefrom as illustrated in Figure 4. When the cork 11 is positioned to permit the contents of the measuring well or compartment to be poured therefrom the face 11' of said cork will prevent liquid within the body por-

tion of the bottle from being poured therefrom as illustrated in Figure 4.

I prefer to employ a cork 11 which is square in plan as illustrated in Figure 5 as by employing such a cork the danger of accidental displacement of the cork is practically eliminated. If the cork were round it might be accidentally moved to an intermediate position to locate the inclined face 12 so that liquid may be spilled from the bottle. By employing a square cork, however, said cork will be positioned as shown in Figures 1 and 2 or as shown in Figures 3 and 4 and in either event liquid within the body portion of the bottle will be prevented from spilling therefrom.

The purpose of the cutaway portion 13 in the top face of the cork is to permit the position of the cork to be readily determined even in the dark, as by seeing the location of the cutaway portion or feeling its position in the dark the position of the inclined face 12 of the cork will be determined.

I claim:

1. A bottle comprising a body portion and a neck portion, a measuring compartment arranged within said neck portion, a passageway leading from said body portion to said measuring compartment, said measuring compartment being adapted to receive predetermined amounts of liquid from the body portion of the bottle whereby the contents of the bottle may be poured therefrom in measured portions, said neck portion being provided with a discharge opening for said measuring compartment, and adjustable means whereby either the passageway leading into the measuring compartment or the discharge opening of said measuring compartment may be closed to the passage of liquid therethrough, said means comprising a cork for the bottle provided with a cutaway portion adapted for arrangement adjacent to said passageway or said discharge opening.

2. A bottle comprising a body portion and a neck portion, a measuring compartment arranged within said neck portion, a passageway leading from said body portion to said measuring compartment, said measuring compartment being adapted to receive predetermined amounts of liquid from the body portion of the bottle whereby the contents of the bottle may be poured therefrom in measured portions, a discharge spout for said measuring compartment, and adjustable means whereby either the passageway leading into the measuring compartment or the discharge spout of said measuring compartment may be closed to the passage of liquid therethrough, said means comprising a cork for the bottle provided with a cutaway portion adapted for arrangement adjacent to said passageway or said discharge spout.

3. A bottle comprising a body portion and a neck portion, a measuring compartment ar-

ranged within said neck portion, a passageway leading from said body portion to said measuring compartment, said measuring compartment being adapted to receive predetermined amounts of liquid from the body portion of the bottle whereby the contents of the bottle may be poured therefrom in measured portions, a discharge spout for said measuring compartment, adjustable means whereby either the passageway leading into the measuring compartment or the discharge spout of said measuring compartment may be closed to the passage of liquid therethrough, said means comprising a cork for the bottle provided with a cutaway portion adapted for arrangement adjacent to said passageway or said discharge spout, and indicating means on said cork for determining the position of same.

20 In testimony whereof, I have hereunto set my hand.

JOSEPH M. KENNEDY.
